UNITED STATES PATENT OFFICE

ELIJAH B. MARTINDALE, OF INDIANAPOLIS, INDIANA.

PAVEMENT AND FLOOR.

SPECIFICATION forming part of Letters Patent No. 286,321, dated October 9, 1883.

Application filed June 11, 1883. (No model.)

To all whom it may concern:

Be it known that I, ELIJAH B. MARTINDALE, a citizen of the United States, residing at Indianapolis, in the county of Marion, in the State of Indiana, have invented certain new and useful Improvements in Pavements and Tiling for Floors, Walks, Streets, and Drive-ways, of which the following is a specification.

My said invention consists in the use of paper, pasteboard, straw-board, tar-board, or other blocks or boards made wholly or in part of the material or other like material of which paper, pasteboard, straw-board, or tar-board is or may be made, by cutting, cementing, concreting, molding, and pressing the same into shape for use in paving and tiling, as herein-after more specifically described.

In the accompanying drawings, which are made a part hereof, Figure 1 is a top or plan view of a section of such pavement as it may be laid, the shape of the blocks and the figure or design being immaterial, the paper or board being so cut and pressed or molded that the edge of the paper will form the surface of the floor or pavement. Fig. 2 is a perspective view of a block.

Such floor or pavement may be made by cementing and pressing together, under very heavy pressure, many sheets of such paper-board, and, when the blocks thus made are dry and hard, cutting them up into blocks of the required size and laying them in a cement,

pressing them together, so that the cut edge of the paper forms the surface of the floor or pavement; or the same may be made by compressing blocks into shape from paper-pulp mixed with clay and mineral as it comes from the paper-engine, and laying the blocks so made close together in cement, with the edge or grain to the surface. Where such pavement is exposed to the weather or standing water, the blocks should be thoroughly waterproofed before laying.

What I claim as new, and desire to secure by Letters Patent, is—

1. A floor, pavement, street, or driveway made of paper, pasteboard, or boards made wholly or partly of paper-pulp pressed and cut into blocks, tiles, or plank, and laid with the edge of the paper forming the surface. 50

2. A pavement made of paper, pasteboard, or other like material pressed, cut, or worked into blocks, and laid with the edges forming the surface.

3. A floor or pavement wherein the edge of paper, pasteboard, or other like material forms the surface of the same. 55

Witness my hand this 8th day of June, A. D. 1883.

ELIJAH B. MARTINDALE.

In presence of—

CHARLES MARTINDALE,
LYNN B. MARTINDALE.
